(57) **CLAIM**

The ornamental design for a necklace stand, as shown and described.

DESCRIPTION

FIG. 1 is a front perspective view of a necklace stand, showing my new design.

FIG. 2 is a top plan view of the invention shown in FIG. 1.

FIG. 3 is a front elevational view of the invention shown in FIG. 1.

FIG. 4 is a rear elevational view of the invention shown in FIG. 1.

FIG. 5 is a left side elevational view of the invention shown in FIG. 1.

FIG. 6 is a bottom plan view of the invention shown in FIG. 1; and,

FIG. 7 is a right side elevational view of the invention shown in FIG. 1.

1 Claim, 7 Drawing Sheets

FIG. 1

FIG. 2

FIG. 3

FIG. 4

FIG. 5

FIG. 6

FIG. 7
